COMPOSITE DIE FOR SHOE PARTS

Arthur W. Altvater, University City, Mo.

Application March 12, 1934, Serial No. 715,155

12 Claims. (Cl. 164—93)

This invention relates to cutting and ornamental dies of a type designed and adapted especially for use in operating on parts for shoe uppers.

5 An object of this invention is to provide a die assembly which will have means for readily interchanging the die members in order to permit the device being used in making a variety of different designs.

10 Another object of the invention is to provide a die assembly suitable for making cut-outs for ventilated shoe uppers with the dies in sections to permit the same die assembly being used for a number of different designs.

15 Another object of the invention is to provide improved securing means in a die of this character whereby a unitary device may secure a number of different die elements firmly in position.

20 Another object of the invention is to provide improved gaging and clamping means for a die assembly of the class described.

Other and specific objects will be apparent from the following detail description, taken in connection with the accompanying drawings, in which—

Fig. 1 is a plan view of the die assembly;

Fig. 2 is an inverted plan view;

Fig. 3 is a plan view of the die assembly with 30 the gage member removed and the stripper plate lifted;

Fig. 4 is a plan view similar to Fig. 3 with the clamping plate removed;

Fig. 5 is a plan view similar to Figs. 3 and 4, 35 with the die elements removed and partly in section to illustrate the unitary securing member;

Fig. 6 is a plan view of a gage member;

Fig. 7 is an elevation of the gage member shown in Fig. 6;

40 Fig. 8 illustrates the several die elements by plan views thereof;

Fig. 9 is a rear elevation of the die assembly;

Fig. 10 is a vertical section on line 10—10, Fig. 1;

45 Fig. 11 is a vertical section on line 11—11, Fig. 4;

Fig. 12 is a vertical section on line 12—12, Fig. 1;

50 Fig. 13 is a vertical section through a die element;

Fig. 14 is a vertical section showing detail construction of the resilient supporting members;

Fig. 15 is a horizontal section in detail on line 15—15, Fig. 9.

55 A plurality of die members, 1, 2, 3, 4, 5, 6 and 7,

each include upstanding cutting or marking edges, and are supported on a base plate 8. Different numbers and designs of such die members may, of course, be used. Spacing means, which will be more particularly described herein, are provided to position the die members with respect to the base plate. A hold-down plate 9, having appropriate openings 10, through which the cutting or marking members extend, is placed over the die members, the plate engaging the top surface of the bases of the die elements. Downwardly extending posts 11, secured to the hold-down plate 9, are adapted to be engaged by a reciprocating bail member 12, as best shown in Fig. 12.

A stripper plate 13 is secured by hinges 14 to the die assembly in a manner which will be later described in detail, but in such a fashion as to permit the stripper plate to be lifted for access to the hold-down plate and the die elements for their placement and removal. A gage and clamp 15 is removably positioned with the assembly, thus providing access for the placement and removal of the die elements.

It will be apparent from this preliminary description that a plurality of different selected die elements may be used with the die assembly, that unitary means are provided for securing such elements firmly in position, and that means are provided for the ready placement and removal of different selected die elements. The particular construction of the several elements and their operation will be apparent from a more detailed description which follows.

The base plate 8 has usual openings 16 through which may pass cuttings severed by the die elements. Sockets 17 are formed in the base plate to receive dowel pins 18 secured to and extending downwardly from bases 19 of the die members. Thus the sockets 17 and the dowel pins 18 provide spacing means between the die members and the base plate 8. Parallel longitudinal slots 20 are formed in the base plate 8 to accommodate the legs 21 of the bail member 12. Fastening plates 22 are secured by screws 23 to the base plate 8 and hold the bail member 12 in position.

A handle member 24 is secured to the rear edge of the base plate 8 by screws 25 and provides means for carrying the die assembly as well as cooperative means for the manual manipulation of the bail member 12.

The arrangement whereby the legs 21 of the bail member 12 engage the downwardly extending posts 11 of the hold-down plate 9, is best shown in Fig. 12. The posts 11 project through holes 26 in the legs 21 (see Figs. 5 and 12). Lon-

itudinal slots 27 are continuations respectively of the holes 26 and accommodate the reduced portions 28 of the posts 11, as shown in Fig. 12. It may be understood that the plate 9 is placed 5 over the die members resting upon the top surface of the bases of the die elements; the bail member 12 is withdrawn to its outmost position; the posts 11 register with and pass through the holes 26 in the legs 21 of the bail member; and 10 then the bail member 12 is forced forwardly, with the reduced portions 28 of the posts 11 clamped in the slots 27 of the bail member. The forward end of each leg 21 of the bail 12 is tapered to provide for drawing the post 11 downwardly to clamp 15 the parts in position, as shown in Fig. 12. It will be seen that the hold-down plate clamps one, or more, or all of the die members in position.

The movement of the bail member 12 is limited by pins 29, secured to the base 8 and positioned in slots 30 cut in the legs 21 of the bail member. Thus, when the bail member is withdrawn the pins 29 serve to bring the holes 26 into proper registry to receive the posts 11.

The die members 5 have appropriate holes 31 to 25 permit the passage of the posts 11 through the bases of the die members.

The dies may be of any specific form but the details of a specific die are shown in Fig. 13. As specifically shown, they comprise a pair of 30 base plates 32 in which is secured the cutting tubes 33. While the device as specifically illustrated includes a plurality of dies for forming the vamps of so-called ventilated shoes, and all of the cutting members are identical, constituting merely a 35 plurality of tubes 33, it will be understood that dies of any particular conformity may be used with the principal invention herein disclosed. Such dies may have cutting edges or embossing surfaces. It will be obvious, of course, that this 40 invention has particular utility in connection with the manufacture of so-called ventilated shoes whereby a plurality of styles may be executed with one set of dies.

In actual practice the die members are numbered as shown on the drawings. A chart is furnished with the assembly indicating the particular die member or members required to produce the different styles for which the assembly is adapted.

50 Resiliently supported posts 34, shown in detail in Fig. 14, form resilient supports for the free end of the stripper plate 13 and one or more of them, four as specifically shown in Fig. 3, function as guides for the hold-down plate 9, the 55 hold-down plate 9 being provided with appropriate holes for their passage, as best shown in Fig. 11.

The specific construction and arrangement of the posts 34 will be understood by reference to 60 Fig. 14. The posts comprise cylindrically shaped members having outwardly extending circumferential flanges 35 which bear against the bottom of the fastening plates 22. An expansion spring 36 has its lower end resting in the bottom of a well 37 of the base 8 and its upper end pressing against the inner surface of the post 34.

The stripper plate 13 is secured by hinges 14 to a resiliently supported table 40 positioned at the rear of the base 8. Downwardly extending pins 41 are secured to the table 40 and pass through appropriate holes in the base 8, as best shown in Fig. 10. Upwardly extending sockets 42 are formed in the bottom of the base 8 concentric with the pins 41 and accommodate heads 75 43 on the pins. Spiral springs 44 are positioned

about the pins 41 and press on the bottom of the table 40 keeping it normally in extended position so that the heads 43 of the pins 41 engage the top of the sockets 42.

It will thus be seen that the stripper plate is 80 resiliently supported; it being attached at its rear edge to a resiliently supported table 40 and it resting on resiliently supported posts 34 near its front edge.

The gage plate 15 is removably attached to the table 40 and may serve either as a gage or clamp, or both, for the work. Its outer edge 45, or an internal edge 46, may conform to a portion of the work as desired.

The gage plate 15 has downwardly extending 85 dowel pins 47 passing through appropriate holes in the table 40 against the ends of leaf springs 48 secured to the bottom surface, as shown in Figs. 9, 10 and 15.

A post 49 extends downwardly also from the bottom of the gage plate 15, is adapted to extend through a rotating collar 50 and has a cross pin 51 adapted to be engaged by a cam surface on the bottom of the collar 50. The collar 50 extends through and is mounted for rotation in 100 the table 40, it being held in position by plates 52. A lever 53 is secured to the collar 50 for its rotation. A slot 54 is cut in the collar 50 to accommodate the cross pin 51 and provides means whereby the gage plate 15 may be readily 105 placed in and removed from the table 40. The cam surface on the bottom of the collar 50 is such that it has two positions of rest, one wherein in the gage plate 15 is spaced slightly above the table 40 and the stripper plate 13, and the second 110 in which it is brought to clamping position against them.

The arrangement of the gage plate 15 is such that it may be readily removed from the assembly to permit lifting of the stripper plate 13 on its hinges, thus providing free access for changing the die elements. By the first movement of the lever 53, after the plate 15 is in position, the gage plate 15 is brought to an initial adjustment in which, if desired, a portion of the work 120 may be slid between the bottom of the plate 15 and the top of the stripper plate 15, to engage an overlying portion of the work in a manner which is understood in the art. By a second movement of the lever 53 the plate 15 may be lowered with respect to the table 40 and thus 125 brought into clamping position to hold the work secure during the subsequent operation.

From the foregoing description and construction and operation of the die assembly will be 130 obvious and its advantages will be apparent. Means have been provided whereby a plurality of die elements may be secured to a base in order that a single die assembly may be used to execute a number of different designs. A single unitary 135 fastening means has been provided whereby one or more, or all, of such die elements may be secured to the base. A combined stripper plate and gage has been provided which is nevertheless removable for easy access to the die elements, which will serve to gage the work by either an external or internal edge, and which will also serve as a clamping member for the work to secure it in fixed position during the stamping operation.

Various changes have been suggested above but it will be obvious that other changes may be made, that various additions may be made and that parts of the invention may be used without the whole, within the scope of the appended 140 145 150

- claims, without departing from the spirit of this invention.
- I claim:
1. A die assembly of the character described including a base, a die member supported by the base and including a base plate and die elements extending from and supported by said plate, a hold-down plate having openings to accommodate the die elements of said die member, and unitary means associated with said base to clamp said hold-down plate in position and thereby secure the die member with respect to the base. 80
  2. A die assembly of the character described including a base, a die member supported by the base, means for locating said member in proper position on the base, a hold-down plate adapted to bear against a portion of said member, and a slide associated with the base and adapted to engage a downwardly extending part of said plate to latch the plate in position. 85
  3. A die assembly of the character described including a base, a plurality of die members, means for locating said die members in proper position on the base, and unitary means for releasably securing any one or more of said members to the base. 90
  4. A die assembly of the character described including a base, a plurality of die members of such conformity that a number of different designs may be performed by using all or only some of said die members, means for spacing said die members on the base, and unitary means for releasably securing any part or all of said members to the base. 95
  5. In a die assembly of the character described having a base and a die member including a base plate and upstanding die elements, the combination including a hold-down plate adapted to engage said base plate, a lug secured to said hold-down plate and extending toward said base, and a reciprocating latch member on said base and adapted to engage said lug. 100
  6. In a die assembly of the character described having a base and a plurality of die members removable from said base, the combination including a stripper plate, a resiliently supported table on one side of the base in the normal plane of the stripper plate and adapted to removably support a gage device, and hinges securing the stripper plate to said table. 105
  7. In a die assembly of the character described having a base and a plurality of die members removable from said base, the combination including a stripper plate, a resiliently supported table on one side of the base in the normal plane of the stripper plate and adapted to removably support a gage device, hinges securing the stripper plate to said table, and resilient supports extending from the base to support a part of the stripper plate opposite said hinges. 110
  8. In a die assembly of the character described having a base and a plurality of die members removable from said base, the combination including a stripper plate, a resiliently supported table on one side of the base, hinges securing the stripper plate to said table, and a gage plate removably supported by the table. 115
  9. In a die assembly having a base, a die member supported by the base, and a table resiliently supported by the base, the improvement comprising a combined clamp and gage on the table including a plate and a cam member adapted to move the plate to one position in which the plate is spaced above the table to permit a portion of the work to be inserted between the plate and the table and adapted to move the plate to a lower position in which the plate clamps the work inserted between the table and the plate. 120
  10. In a die assembly having a base, a die member supported by the base, and a table resiliently supported by the base, the improvement comprising a combined clamp and gage on the table including a plate, a pin extending downwardly from the plate, a collar for the pin revolvably mounted in the table, and a cross-head on the pin adapted to cooperate with a cam surface on the lower face of the collar. 125
  11. In a die assembly having a base, a die member supported by the base, and a table resiliently supported by the base, the improvement comprising a combined clamp and gage on the table including a plate, a pin extending downwardly from the plate, a collar for the pin revolvably mounted in the table, and a cross-head on the pin adapted to pass through a slot in the collar and to cooperate with a cam surface on the lower end of the collar. 130
  12. A die assembly of the character described including a base, one or more die members having upstanding die elements, one or more elements depending from said members, said base having means to accommodate a plurality of said depending elements for locating said members in proper position on the base, and unitary means for simultaneously latching a plurality of said elements to the base. 135
